J. A. RANKIN.
CATTLE GUARD.
FILED JULY 12, 1921.

1,442,495

UNITED STATES PATENT OFFICE.

JOHN ALEXANDER RANKIN, OF CLOVER BAR, ALBERTA, CANADA.

CATTLE GUARD.

Application filed July 12, 1921. Serial No. 484,246.

To all whom it may concern:

Be it known that I, JOHN ALEXANDER RANKIN, of the post office of Clover Bar, in the Province of Alberta, Canada, have invented certain new and useful Improvements 5 in Cattle Guards, of which the following is the specification.

The invention relates to improvements in cattle guards and particularly to a cattle 10 guard as used on railroads and an object of the invention is to provide a guard which will effectively prevent cattle or other such roving animals from wandering along the track at a crossing and which is also designed 15 to permit at all times of the free passage of the trains.

A further object of the invention is to construct a guard presenting normally open gates adapted to be closed across the track 20 and actuated by the approaching animal and designed so that they will forcibly strike the animal and in so doing cause it to immediately withdraw and further which are arranged so that they automatically open after 25 the animal has withdrawn.

A still further object is to construct the guard so that it can be readily installed and so that it can be positively relied upon to do the work for which it is designed.

With the above more important objects in view the invention consists essentially in the arrangement and construction of parts hereinafter more particularly described and later pointed out in the appended claims, 30 reference being had to the accompanying drawing in which:—

Fig. 1 is a plan view of the complete cattle guard and as it appears with the gates in the normal position, that is open.

Fig. 2 is a longitudinal sectional view 40 through the cattle guard, the section passing centrally of the track.

Fig. 3 is a vertical sectional view through one side of the cattle guard showing the 45 operating gears and other associated parts.

In the drawing like characters of reference indicate corresponding parts in the several figures.

As is customary the cattle guard is placed 50 in the usual position across the track and by the side of the crossing. The railroad track rails 1 and 2 are carried by the customary ties or sleepers 3. In the present disclosure the road is considered as crossing 55 the track at the left hand side of the drawing.

When the cattle guard is to be installed I first dig a shallow pit 4 underneath the tracks at the side of the crossing and locate a number of supporting beams or foot pieces 60 5 and 6 in the bottom of the pit, these carrying lengthwise extending joists or beams 7, 8, 9 and 10, the beams 8 and 9 being preferably immediately underneath the track rails and those 7 and 10 positioned somewhat to 65 the sides of the track rails. The rails are spiked directly to the beams 8 and 9 as indicated at 11. Parallel end beams 12 and 13 extend transversely of the track and are mortised into the ends of the beams 7, 8, 9 70 and 10 and permanently fastened thereto. This under beam structure forms a framework which contains a central platform 14 located between the beams 8 and 9 and two side platforms 15 and 16 located between 75 the beams 7 and 8, 9 and 10.

The platforms are all carried by a cross shaft 17 having suitable bearings in the beams 7, 8, 9 and 10 and here it will be observed that the shaft is disposed to the side 80 of the transverse axis of the platforms and that the long ends of the platforms are fitted with weights 18 which positively maintain the platforms in a horizontal position with the long ends engaging with a stop 85 beam 19 set in from the end of the under frame. Accordingly the platforms are maintained approximately in the plane containing the bases of the rails and obviously should an animal step on the left hand or 90 unsupported end of any platform it will swing down and effect the rotation of the shaft as the platforms are fastened permanently to the shaft. This movement which is produced by the animal is utilized to 95 rotate the engaging gears which control and operate the gates shortly described.

At each side of the frame and immediately adjoining the ends of the shaft I locate a specially cast preferably hollow base block 100 20 which is permanently set in the ground and carries a pair of vertically disposed spindles 21 and 22 and is fitted with a vertically extending socket 23. Each base block is provided with a large gear wheel 24 rotatably mounted on the spindle 22 and with a smaller gear wheel 25 rotatably mounted on the spindle 21, the gear wheels meshing.

The projecting ends of the shaft 17 are fitted with similar gear wheels 26 and 27 and 110 these mesh with small gears 28 and 29 attached to or formed as an integral part of

the gears 24. The sockets 23 receive pivotally pivot spindles 30 and 31 formed as extensions of the outer ends of the gates 32 and 33. These gates are of a light yet 5 strong construction and they are adapted when swung inwardly to meet and lap slightly at the centre of the track. To the spindles 30 and 31 I secure pinions 34 and 35, these being designed to mesh with the 10 gears 25.

When the platforms are in the normal or horizontal position the gates are open or parallel with the track in which position they are shown in Fig. 1. The engaged 15 train of gears and pinions at the opposite sides of the platform are of such a ratio that the down swinging movement of the short end of any platform will effect the simultaneous in-swinging of the gates, the 20 swing being somewhat more than ninety degrees. The gates can be readily set by lifting them to raise the spindles and withdraw the teeth of the pinions 34 and 35 from the teeth of the gears 25 and then, 25 after swinging the gates to make an adjustment, dropping the spindles to re-engage the teeth of the said pinions and gears.

The down-swinging movement of the short or left hand ends of the platforms are 30 limited by the engagement of the platforms with the cross beam 5.

According to the above construction it will be obvious that should an animal attempt to wander from the road crossing on 35 to the tracks it will step on the free end of one or the other of the platforms and the said end will go down quickly. The intermeshed gears and pinions are accordingly turned quickly with the result that both the 40 gates swing in quickly and not only bar the progress of the animal but in all probability will hit the head of the animal. This coincident barring and striking action will effectively act to make the animal quickly withdraw. 45 Immediately the animal withdraws the platform, being relieved of its weight, swings back to normal position under the action of the attached weight 18 and in this connection it is remarked that the long

end of the platform must be heavy enough 50 to return the gates to their normal out position immediately the weight of the animal is removed from the platform.

The customary fence posts are indicated at 36 and 37 and the usual post braces at 55 38 and 39.

Whilst I have described the guard as embodying three platforms, I do not wish it to be restricted to this precise number as one or more could be used as occasion 60 demands.

Further, I have not shown the gears and pinions as enclosed. A suitable housing will be provided to enclose them to protect them from the weather. As the structure was 65 more easily shown without such coverings I have omitted them.

What I claim as my invention is:

1. In a cattle guard for railways, a normally horizontal platform disposed between 70 the track rails, a rotatably mounted cross shaft passing transversely of the track and pivotally supporting and permanently attached to the platform, a pair of gates located at the sides of the track and adjacent 75 the ends of the shaft and adapted to swing inwardly across the track, a gear wheel permanently secured to each end of the shaft, a pinion permanently secured to each gate, a train of gears connecting the pinions of 80 the gates with the gear wheels of the shaft, said gears and pinions being adapted to close the gates across the track upon an animal stepping on one end of the platform.

2. In a cattle guard, the combination of a pivoted platform, a rotatable shaft operable by movement of said platform, a casting formed with a socket, a swinging guard having a post rotatably mounted in said socket 90 and intermeshing gears carried by said post, casting and shaft.

Signed at Edmonton this 4th day of May, 1921.

JOHN ALEXANDER RANKIN.

In the presence of—

J. C. SHERRY,
W. E. HANSFORD.
